UNITED STATES PATENT OFFICE.

ISAAC L. PULVERMACHER, OF LONDON, ENGLAND, ASSIGNOR TO JOHN EDWARD HETHERINGTON, OF CINCINNATI, OHIO.

IMPROVEMENT IN VOLTAIC PILES OR BATTERIES.

Specification forming part of Letters Patent No. 177,273, dated May 9, 1876; application filed March 14, 1876.

To all whom it may concern:

Be it known that I, ISAAC LOUIS PULVERMACHER, of London, England, have invented certain Improvements in Volta-Electric Batteries, of which the following is a specification:

This invention has for its object the construction of volta-electric batteries by means of cone-shaped disks of positive and negative metal, arranged upon a central stem; and it consists in the peculiar construction and arrangement of the several parts, and their combination with each other, as will be herein-after specified.

In the drawings, Figure 1 is a sectional view, showing a series of copper and zinc plates, A B, mounted upon a hollow central stem, C, which supplies the exciting liquid through slots corresponding with the elements, the zincs being held in place within the hollows of the copper plates by means of pins, the heads and points of which rest upon burred-in shoulders of each copper plate of the series, the zinc being insulated, or preserved from contact with the copper, by means of threads or tissues of an absorbent fibrous texture.

Figs. 2 and 3 represent, respectively, edge and plan views of a plate of circular form, provided with tongues *a a*, projecting from the edge, and prongs *b b*, turned at right angles on the same, to serve as hooks or claws for taking hold of the corresponding plate of the next element, when the said elements are separated farther apart for the production of quantity electricity of low tension, by bringing all or groups of zincs in contact, as well as all the copper, thus forming an element of large surface, but which plates, as elements forming the battery in the ordinary position, are so arranged in proximity, and the claws or prongs *b b* kept clear of the corresponding plates of the neighboring elements, as to maintain, when the elements are excited, electricity of high tension through the contact effected by bent-up tongues *c c*, as shown in Fig. 4, which arrangement will now be described.

In this form, which is represented in section, a series of dished or cone-shaped disks, of negative metal, A, and positive metal, B, is arranged in voltaic order, in a superposed manner, the two disks of each pair having a

film or tissue of fibrous material interposed, as before stated. Each negative, or it may be each positive, disk is slotted radially, as in Fig. 5, which may be done in the stamping-out process. From these disks the tongues *c c*, before mentioned, may be bent up at right angles, the same being situated at intervals, and arranged for the opposite metal of the next pair of plates or disks, as elements, to rest upon and form contact-points. The length or height of these tongues will be in proportion to the distance at which the elements have to be kept apart.

The plates may be slotted from the periphery, as at F in Fig. 6, so as to enable them to be slipped onto the stem C sidewise.

The central stem may consist of a flexible tube, C, of rubber or other suitable material, strained over a central corrugated or fluted stem, B, of rigid material—say ebonite—to retain the rubber tube in an erect, non-yielding condition. The flexible tube may be slotted, at intervals, by means of a lancet or some sharp instrument, the slits corresponding to the flutes or corrugations in the central stem, down which the exciting fluid can be caused to flow on pressure being applied to a charged ball or receptacle (not shown) on its free end.

The flutes or corrugations in the rigid stem or core D are so arranged in proportion to the slits in the tube C that the spray of liquid is diffused through the whole of them, so as to thoroughly moisten the fibrous material without waste. Should, however, the quantity of liquid supplied be in excess, I provide a receptacle, E, at the bottom, into which the overflow can run, and from time to time be returned to the charging ball or receptacle, as desired.

If thread is used as the fibrous body between the disks, I prefer to perforate the plate and sew it in in concentric rings, as shown in Fig. 6, the thickness of the thread being sufficient to prevent surface contact between the two metals of the element, and to permit free access of air at all times into and between them.

I sometimes make my disks of thread-wrapped wire, of negative metal, wound into a spiral form until the proper diameter is attained, as in Fig. 7, leaving a suitable open-

ing at the center to permit the disk to be slipped onto the central tube.

For establishing voltaic contact between these spirally-formed disks of one element with the dished zinc disks of the element beneath it, I provide the latter with metal prongs or tongues *c*, as in Fig. 8, fastened in the concave side of the disk. These prongs must be placed in contact with the wire of the spirally-formed disk between the thread-wrappings of the same, or, rather, between the strands of the thread-wrapping.

I have already obtained a patent for the within-described invention in Great Britain, which patent bears date November 16, 1874, No. 3,937.

I claim—

1. The arrangement, as herein shown, of a series of copper and zinc disks, dished or coned in alternate order, with a fibrous absorbent material interposed between members of the same element, upon a hollow central stem, supplied with the exciting fluid, and slitted or perforated to cause the passage of the exciting fluid from the tube to the absorbent material between the disks, the whole to form a battery, substantially as set forth.

2. The combination of a flexible tube, *C*, and

a rigid fluted or corrugated central core, *D*, with concave or dished copper and zinc disks *A B*, to form a battery, substantially as herein shown and described.

3. The radially-slotted disks shown in Fig. 5, provided with tongues *c c*, at intervals, for the opposite metal disk of the adjoining element to rest upon, substantially as herein set forth.

4. The disk shown in Fig. 6, having a slot, *F*, from the periphery to the center, and threads sewed into it in concentric circles, as fully shown in the drawings, and for the purposes set forth.

5. In batteries formed of disks on a hollow central stem, the disk shown in Fig. 7, constructed of thread-wrapped wire, wound spirally until a suitable diameter is attained and an aperture left at the center to engage the central stem, as set forth.

In testimony whereof I have hereunto set my hand in the presence of two witnesses.

ISAAC LOUIS PULVERMACHER.
